UNITED STATES PATENT OFFICE.

ERIK L. KRAM, OF CHICAGO, ILLINOIS.

SWITCH AND SWITCH BOX.

Application filed September 20, 1920. Serial No. 411,575.

To all whom it may concern:

Be it known that I, ERIK L. KRAM, a citizen of the United States, residing at Chicago, in the county of Cook and State of Illinois, have invented certain new and useful Improvements in Switches and Switch Boxes, of which the following is a specification.

This invention relates to electric switches and has for its object the production of an electric switch, suitable to be mounted in an enclosing box together with a box for the purpose suitably arranged not only to enclose the switch but to prevent persons using the switch from opening or closing the same except when the box itself is closed. Means are provided whereby the switch may be conveniently opened when the box is closed, but the box cannot be opened when the switch is closed, and the switch cannot be closed when the box is opened. Other objects of the invention will appear from the accompanying drawings and the description thereof.

Of the accompanying drawings Fig. 1 is an elevation of a switch, with a portion of the box in section, which embody the features of my invention; Fig. 2 is an end elevation of the same; Fig. 3 is a section 30 along the line 3—3 of Fig. 1; Fig. 4 is a side elevation of the closed box; Fig. 5 is a section of the same along the line 5—5 of Fig. 4; Fig. 6 is a side elevation of the box with portions thereof broken away; Fig. 7 is a section along the line 7—7 of Fig. 6; Fig. 8 is an end view of the box with a portion broken away; Fig. 9 is an elevation of a modified form of switch; and Fig. 10 is a sectional view along the line 10—10 40 of Fig. 9.

The form of switch which I prefer is mounted upon a base 10 and supported by the bearings 11 and comprises a rod 9 rotatably mounted in the bearings, and having a handle 12 fixed thereto. In this instance I have shown the rod 9 with a square cross-section, that portion within the bearings being rounded, but it is to be understood that the shape of the cross-section is not material to my invention. Enclosing the rod 9 is a tube 14 of any suitable insulating material; and the knife blades 15 of the switch are fixed to this tube, so that the blades are nonrotatable with reference to the rod 9. Clips 13 are mounted on opposite sides of each blade so as to be in electrical contact therewith at all times, and are fixed to the base-board 10 in any suitable manner, and the clips are connected in any ordinary manner to the fuse plug socket of the fuse 16 which is mounted in any ordinary wire connector 8.

By this arrangement it will be seen that when the handle 12 is properly operated the outer ends of the switch blades 15 will be elevated or lowered as the case may be. On the base-board 10 are mounted other suitable clips 8' for coacting with the knife blades when the switch is to be closed. Although I have shown a single throw switch, it is obvious that the same general arrangement could be applied to a double throw switch.

The switch block 10, with the switch thereon, is mounted in a box 17 of suitable shape, and the rod 9, with the handle 12 thereon, projects out of one side of the box through a suitable opening 38. A lid 39 is suitably hinged to the box 17, the hinges thereof being at the rear side of the box; any suitable form of latch may be used to lock the lid closed. I prefer the latch 23 pivoted to the front side of the lid and so arranged that a detent 40 thereon enters an opening 24 in the box and holds the lid closed, a spring 41 forcing the detent into the opening.

To prevent opening the lid when the switch is closed, the latch 23 is so placed that the handle 12 will hold it in the closed position until the switch is fully opened. But by turning the handle 12 to the vertical position, and thus opening the switch wide, the detent may be removed from the opening 24 and the box lid raised. To prevent closing the switch when the lid is opened a collar 18 is fixed to the rod 9 adjacent to the front bearing 11, and a recess 19 is provided in the collar into which a detent 20 passes when the arm 12 is in its vertical position, and this detent, by means of the spring 42, thus holds the arm 12 in its vertical position, and thus the switch wide open, until the lid is closed. When the lid is closed a finger 21 is forced downwardly by the lid against the detent 20 and the collar 18 is released from the detent, and the switch may be closed. Any suitable means such, as a lug 22, fixed to the lid, may be used for forcing the finger downwardly. In order to prevent the switch from being thrown backwardly beyond the vertical position, in case of a single throw

switch, I provide lugs 43 and 44 upon the bearing 11 and the collar 18, which come in contact with each other when the switch blades reach the vertical position.

- 5 In order to provide for changing the means for passing wires into the switch box ends I provide removable end pieces 45. The end pieces have flanges 46 on the lower edge which pass under fingers 47 formed in 10 the bottom of the box, and the end pieces are placed against flanges 48 formed on the sides of the box, and are held in place by means of spring clips 49 fixed to the sides of the box. By this means end plates having any desired 15 number or size of wire openings 50 may be used.

Figures 9 and 10 represent a modified form of switch. This switch comprises the pivoted blades 33, which are fixed to an insulation bar 32, and the bar is operated by the rod 30 rotatably mounted in the bearings 31, so that when the end of the rod 30, slidably passing through an opening in the bar 32, is raised or lowered, the blades 33 will be 20 raised accordingly and the switch accordingly opened or closed. It is to be understood that this modified form of switch may be enclosed in a box similar to the one hereinabove described, and the various interlocking means described with reference to that 25 box and switch may be applied as well to the modified form of switch. An insulation sleeve 35 surrounds rod 30 between the bearings 31 and passes through the openings 36 30 in the support of the front blade of the switch.

I claim as my invention:

1. The combination of a box and an electric switch, said switch comprising a rod 40 rotatably mounted in said box and extending outside of the box, a switch plate fixed to

said rod and insulated therefrom, a wire connector arranged to coact with said plate when the plate is in its closed position and another wire connector arranged to coact with said plate in all positions of the plate, said box having a lid, and means to prevent opening of said lid when said switch is closed, said means comprising a handle fixed to said rod outside of said box, and a detent 45 fixed to said lid, said box having a recess adapted to receive said detent, and said handle arranged to hold said detent in said recess when said switch is closed, and means to prevent closing of said switch when said box is open, said means comprising a collar fixed to said rod, and a detent pivoted 50 to said box, said collar having a recess therein adapted to receive said detent when said box and switch are open, and means for forcing said detent from said recess when said lid is closed.

2. The combination of a box and an electric switch, said switch comprising a rod 55 rotatably mounted in said box and extending outside of the box, a switch blade fixed to said rod and insulated therefrom, a wire connector arranged to coact with said blade when the blade is in its closed position and another wire connector arranged to coact 60 with said blade in all positions of the blade, said box having a lid, and means to prevent opening of said lid when said switch is closed, said means comprising a handle fixed to said rod outside of said box, and a detent 65 fixed to said lid, said box having a recess adapted to receive said detent, and said handle arranged to hold said detent in said recess when said switch is closed.

In testimony whereof, I hereunto set my 70 hand.

ERIK L. KRAM.
